UNITED STATES PATENT OFFICE.

ALEXANDER GORDON, OF DETROIT, MICHIGAN.

CIGAR-BUNCHING MACHINE.

SPECIFICATION forming part of Letters Patent No. 693,265, dated February 11, 1902.

Application filed April 8, 1901. Serial No. 54,881. (No model.)

To all whom it may concern:

Be it known that I, ALEXANDER GORDON, a citizen of the United States, residing at Detroit, in the county of Wayne and State 5 of Michigan, have invented certain new and useful Improvements in Cigar-Bunching Machines, of which the following is a specification, reference being had therein to the accompanying drawings.

10 The invention relates to cigar-bunching machines; and it consists in the peculiar construction of the parts, and especially in the construction of a presser which bears upon the bunch during the rolling thereof.

15 The invention further consists in details of construction, as hereinafter described and claimed.

In the drawings, Figure 1 is a longitudinal section through the machine, substantially 20 on line $\alpha\alpha$, Fig. 2. Fig. 2 is a cross-section. Fig. 3 illustrates some of the parts shown in Fig. 1 on a larger scale, and Fig. 4 is a cross-section on line yy , Fig. 3.

25 My improvements are shown as applied to cigar-bunching machines of that type comprising a reciprocating bunching-table, a bunching-roll, a bunching-apron, and a tension device therefor, which is positively actuated to govern the pressure on the bunch during the rolling.

30 In detail, A designates the frame of the machine, which may be of any suitable construction.

35 B is a shaft extending longitudinally of the frame.

C represents cross-guides near the upper portion of the frame, in which the reciprocating bunching-table D is slidingly secured, and E is a bunching-roll journaled in bearings in 40 the frame just above the path of the table D. The table D is provided at opposite sides with a rack member F, which meshes with pinions G, secured to a shaft H parallel to the shaft B. The shaft H is actuated by a 45 pinion I thereon, which engages with a segmental rack J, and the latter derives its movement from a cam-wheel K, sleeved upon and driven by the shaft B.

50 To the forward edge of the bunching-table D is secured one end of the apron L, which extends across said table and is secured at its opposite end to a reel M, journaled in bear-

ings in the frame above the plane of the table. This apron is of sufficient length to form a pocket a by the slack thereof between 55 the inner edge of the table D and the bunching-roll E. The reel M is positively driven to pay out or take up the apron as required, preferably by means of a pinion N upon the reel-shaft M', the pinion O, sleeved upon the 60 shaft H, and the intermediate pinion P. The pinion O derives its movement from a segmental rack J', similar to the rack J and also actuated by the cam-wheel K. The engagement between this cam-wheel K and the 65 racks J and J' is preferably formed by providing said wheel with cam-grooves upon its opposite faces, with which pins in the racks J and J' engage.

With the parts as thus far described the 70 movement of the shaft B is imparted to the cam-wheel K. The rotation of this wheel will cause the reciprocation of the segmental racks J and J', which in turn actuate the pinions I and O, the former rotating the shaft H and 75 pinions G thereon and imparting a reciprocating movement to the racks F on the table D and the latter, through the medium of the intermediate gear-wheel P, imparting a rotary movement to the pinion N and reel M. 80 The shape of the cam-grooves in the wheel K is such as to impart a differential movement to the segmental racks J and J' and the mechanisms operated thereby. The relative movement is such that the bunching-table is first 85 moved to carry its rear edge beneath the roll E to close the pocket in the apron L, the roll M being moved only to take up the slack without contracting the size of the pocket. In the further operation the table D is temporarily arrested while the reel M is rotated 90 to take up the apron and contract the pocket, thereby compressing the bunch. After the pocket has sufficiently contracted the table D resumes its movement and the reel M is suitably moved to maintain the uniform tension 95 upon the bunch during its rolling.

The rolling of the bunch by the mechanism before described while ordinarily satisfactory has nevertheless certain defects which render the rolled bunch inferior in quality to that produced by handwork. In order to improve the quality of the product, I have provided my machine with a yielding presser 100

which bears upon the bunch during the rolling operation in a similar manner to the pressure of the hand of a workman in rolling a bunch on a table. This presser also serves 5 to form the bunch, giving it the tapering ends which are desired.

As shown, the presser is formed by a coiled spring R, which extends across the frame just above the path of the table and in rear 10 of the bunching-roll E. This spring is secured at its opposite ends to the frame, and one or both ends may be adjustable to alter the tension of the spring. This adjustment I have shown as formed by attaching the 15 ends of the spring to a threaded rod b, engaging a correspondingly-threaded aperture in the frame, so that by turning said rod the tension of the spring is altered.

In operation when the pocket is closed and 20 the loop containing the bunch mounts upon the table it will be forced up beneath the spring R, raising the latter, so that it will exert its tension to press downward upon the bunch during the subsequent rolling. This 25 pressure weakens from the ends toward the center, and will thereby have the result of compressing the ends of the bunch to a greater degree and giving it the required tapering form. In order to prevent the possibility of 30 the bunch forcing the spring R rearward instead of upward, I connect to said spring at one or more points a spring-guide S, which is pivoted at its rear end to a rod S' and holds said spring from rearward movement while 35 permitting of a free vertical movement.

Although I have described the presser as being formed of a coil-spring, I do not desire to be limited to this precise form, as it is obvious that other yielding pressers might be 40 employed which would have the same effect upon the rolling of the bunch.

In order to provide means for adjusting the size of the bunch, I preferably form the reel M with a peripheral sleeve M², which is secured to the center of the reel by a set-screw c. When it is desired to increase or decrease the size of the bunch, the set-screw is loosened and the sleeve M² turned one way or the other to give the necessary adjustment.

50 What I claim as my invention is—

1. In a cigar-bunching machine, the combination with a bunching-table, a bunching-roll and an apron, of a differentially-yielding

presser adapted to bear against the bunch adjacent to said roll with a greater pressure at 55 the ends than at the center thereof whereby a tapering shape is imparted to the bunch.

2. In a cigar-bunching machine, the combination with the apron and coöperating means for forming a closed pocket therein 60 and rolling the bunch, of a flexible bar extending longitudinally of and in adjacence to said pocket and contained bunch and laterally pressed thereagainst.

3. In a cigar-bunching machine, the combination with apron and coöperating means for forming a closed pocket therein and rolling the bunch, of a laterally-spring-pressed 65 flexible bar extending longitudinally of and bearing against said pocket and contained 70 bunch during the operation of rolling.

4. In a cigar-bunching machine, the combination with a frame, a reciprocating bunching-table, the roll and the apron adapted to coöperate to roll the bunch upon said table in 75 a pocket in said apron and in adjacence to said roll, of a coil-spring extending across said frame parallel to and in rear of said roll and above the plane of said table, whereby in the rolling of the bunch said spring will 80 exert a yielding pressure thereagainst.

5. In a cigar-bunching machine, the combination with a reciprocating bunching-table, the roll and the apron, of a coil-spring supported at its ends and extending across said 85 frame parallel to and in rear of said roll and above the plane of said table, and an intermediate connection to said spring permitting of free vertical movement thereof but preventing rearward movement.

6. In a cigar-bunching machine, the combination with the reciprocating table and the bunching-apron connected at one end to said table, of a driven reel to which the opposite end of said apron is attached, said reel being 95 provided with an adjustment for altering the slack in said apron, comprising an outer sleeve to which the apron is attached and means for adjustably locking said sleeve to the inner driven member.

In testimony whereof I affix my signature in presence of two witnesses.

ALEXANDER GORDON.
